TOY AIRPORT TERMINAL BUILDING

Victor G. Reiling, Jr., East Aurora, N.Y., assignor to
The Quaker Oats Company, Chicago, Ill.

Filed Dec. 6, 1972, Ser. No. 312,589

Term of patent 14 years

Int. Cl. D21—01

U.S. Cl. D34—15 LL

FIG. 1

FIG. 2

FIG. 3

FIG. 4

FIG. 5

FIG. 6

FIG. 1 is a front perspective view of a toy airport terminal building showing my new design;

FIG. 2 is a side elevational thereof as viewed from the left in FIG. 1;

FIG. 3 is a side elevational thereof as viewed from the right in FIG. 1;

FIG. 4 is a rear elevational thereof;

FIG. 5 is a top plan view thereof on a reduced scale; and

FIG. 6 is a top plan view thereof on the same scale as FIG. 5 but with the parts in different position.

I claim:

The ornamental design for a toy airport terminal building, substantially as shown and described.
